Primary Examiner — Thomas Johannes*(74) Attorney, Agent, or Firm* — Marshall, Gerstein & Borun LLP; James J. Napoli; Richard M. LaBarge(57) **CLAIM**

The ornamental design for a dispenser package, as shown and described.

DESCRIPTION

FIG. 1 is a front, top, and side perspective view of a first embodiment of a dispenser package showing our new design; FIG. 2 is front elevation view thereof; the rear elevation view is the same;

FIG. 3 is a side elevation view thereof; the opposite side elevation view is the same;

FIG. 4 is a top plan view thereof;

FIG. 5 is a front, top and side perspective view thereof with the re-sealable lid in an open position;

FIG. 6 is a top plan view of an inner package that forms a component thereof;

FIG. 7 is a front, top and side perspective view of a second embodiment of a dispenser package showing our new design; FIG. 8 is side elevation view thereof; the opposite side elevation view is the same; and,

FIG. 9 is a front elevation view thereof; the rear elevation view is the same.

The words that appear in the photographs are not part of the claimed design, nor is the precise overall length, width, and height of the outer carton seen in the photographs; the special dot-dash broken line defines the bounds of the claimed design and forms no part of the claimed design.
